UNITED STATES PATENT OFFICE.

JOSEPH M. RHODES, OF COVINGTON, INDIANA.

IMPLEMENT FOR CARRYING WHEELS.

SPECIFICATION forming part of Letters Patent No. 608,479, dated August 2, 1898.

Application filed October 15, 1897. Serial No. 655,263. (No model.)

To all whom it may concern:

Be it known that I, JOSEPH M. RHODES, a citizen of the United States of America, residing at Covington, in the county of Fountain 5 and State of Indiana, have invented certain new and useful Improvements in Implements for Carrying Wheels; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 This invention relates to certain new and useful improvements in implements for lifting wheels of vehicles, the object of my invention being to provide a cheap, simple, and effective implement for lifting vehicle-wheels, 20 so that they may be handled with the tires thereon and placed into a tank for the purpose of cooling and tempering the tire while on the felly of the wheel.

The invention consists in the combination 25 of a pair of connected bars which are held in sliding engagement with each other by means of loops attached to the end of each bar so as to embrace the bar adjacent thereto, the bars also being provided with depending 30 hooks made of flat pieces each having a quarter-turn adjacent to the bars to which they are attached, they also being provided at their ends with upwardly-projecting portions, the ends of which are beveled, as will be hereinafter fully set forth.

In the accompanying drawings, which illustrate my invention, Figure 1 is a perspective view of a wheel carrier or lifter constructed in accordance with my improvement. Fig. 2 40 is a plan view, and Fig. 3 a detail perspective view, of one of the hooks detached.

A A' refer to two frames, each being made up of parallel bars *b b*, which are connected to each other by cross-bars *b'*, beyond which are located the handles *c*. The ends of each of the bars *b* have rigidly attached thereto loops *d*, which embrace the bar adjacent thereto, so as to provide means for connecting the frames A A' in sliding engagement with 45 each other. The loops *d* are preferably made up of strap metal, the ends being secured to the upper and lower edges of the bars *b*, and while these loops hold the frames in sliding

engagement with each other they will prevent the frames being separated.

To the frames A A', which are adjustable longitudinally upon each other by means of the connections hereinbefore described, are attached hooks *E*, preferably made up of flat bars of metal having at their upper ends an opening *e*, through which passes a bolt or screw for attaching the same to the bars *b*, said bars being recessed to receive the upper end of the hook. Below the point of attachment of the hooks with the bars *b*, the hooks 60 are given a quarter-turn, as shown at *e'*, and the lower end of the depending member of said hooks is bent to provide a horizontal portion *e²*, having an upwardly-projecting member *e³*, the inner edge of which is beveled. 65

In practice, after the tire has been heated and placed on the wheel the implement hereinbefore described is used for handling the wheel, which is usually placed upon trestles. The frames are first drawn outwardly and are 70 then placed in line with the wheel and pushed inwardly or toward each other until the tire engages with the flat portion of the hooks. Then by raising the carrier the lower portions 75 of the hooks will engage with the tire and 80 rim or felly, and the wheel may be carried and placed in a tank containing water, so as shrink and temper the tire. The wheel being held securely by the carrier can be tilted or manipulated in any manner desired.

Having thus described my invention, what I claim as new, and desire to secure by Letters Patent, is—

In an implement for lifting wheels, the combination of a pair of bars each pair of bars 90 being transversely connected by a cross-bar and in sliding engagement with the bars of the adjacent frame by means of loops *d*, of hooks rigidly secured to the bars, the upper portion thereof having bends *e*, the lower 95 portions of the hooks being bent horizontally as shown at *e²* and thence upwardly to provide a vertical member *e³* the end portion of which is beveled, substantially as shown and for the purpose set forth.

In testimony whereof I affix my signature in presence of two witnesses.

JOSEPH M. RHODES.

Witnesses:

JOHN G. EVANS,
HOMER SEWELL.
